UNITED STATES PATENT OFFICE.

WILFRID V. N. POWELSON AND WARREN TRAVELL, OF NEW YORK, N. Y.

ART OF LAUNCHING AIRSHIPS FROM MOORINGS AND DEVICE THEREFOR.

Application filed September 6, 1921. Serial No. 498,606.

This invention relates to improvements in the art of launching airships from moorings, and devices therefor.

In the art, as heretofore practiced, there has been no means provided for definitely and accurately determining whether the upward and downward forces acting on an airship are properly distributed previous to its setting forth on a flight from a mooring. With airships of small size, it has been customary to handle them during housing operations by means of a large number of men on the ground, but with the increase in their size, this handling by man power is being superseded by mechanical mooring devices such as towers and guy line systems. The handling of airships by men on the ground provided a rough means for determining whether the vertical forces were properly distributed, but even this rough check is lacking when launched from tower or guy lines. When the head end of an airship is attached to a tower, the ship may be floating in a horizontal position with the appearance of having the vertical forces in balance, and at the same time there may be a considerable vertical force acting between the head end of the airship and the tower. If released from the tower under such an unbalanced condition, one end may fall to the ground, resulting in damage or destruction of the airship. It is an object of this invention to provide means by which to obviate such risk.

The invention comprises the provision and the combination with the airship, of one or more powerful tension devices each having means to indicate the relative degree of tension to which it is subject from time to time. This, by measuring or comparing the forces acting vertically on the airship, constitutes means for governing the disposition of substance on board so that the center of buoyancy and center of gravity come into vertical relation while the ship is moored with its axis horizontal. When these are so located an airship on being released from its mooring will rise on even keel; but when not so located, there will be a turning movement caused by the vertical forces which will cause the craft to rotate in a vertical plane with its longitudinal axis approaching the vertical.

When an airship is moored between two towers or by guy lines, the determination of the relative positions of the centers of buoyancy and gravity is, according to the inven-

tion, accomplished by means of tension measuring devices, incorporated in two approximately vertical lines fastened to the airship at a distance apart longitudinally, preferably at or near its ends. By means of such devices, the difference between the vertical forces acting on the airship may be measured. Knowing the location of the center of buoyancy, and attaching these two vertical lines to the airship at points equally distant therefrom, the center of buoyancy will be over the center of gravity when the tension in these two lines has become equal. If, on making the measurement, they are not equal, weights on board should be shifted, until these two tensile stresses are thus equalized. If the points of attachment of these lines to the ship are not equidistant from the center of buoyancy, the tensile stresses in them should become inversely as their respective distances from the center of buoyancy.

It is possible to arrive at this condition of equilibrium when the airship is moored to a single tower and by the use of only one tension-measuring device. If the bow of the ship is closely attached to the tower, the fastening line is paid out a short distance. The ship will take a position at an angle to the horizontal which will vary according to the relative amounts of the unbalanced vertical forces and the horizontal forces (such as wind pressure) acting upon the airship. By shifting of weights on board the ship may be changed to floating with its longitudinal axis horizontal. Assuming this done, and that its center of buoyancy is at its center of length, a vertical line is attached to the bow with means for measuring the tension therein. By this line, the bow is then pulled down until the tower attachment line is horizontal and therefore is transmitting no vertical stresses. The tension in the vertical line is then measured, or the indication thereof noted; after which the stern of the vessel is tied by a line to a fixed point beneath. Ballast or other weights are then shifted on board until the tension in the vertical bow line is one-half of that previously registered. The center of buoyancy is then over the center of gravity; and if the attachment lines are cast off simultaneously the airship will rise with even keel.

This invention may also be used for insuring the safety of launching airships which are loaded so as to be heavier-than-air at the

start of flight. Assuming that the cruising airship is moored between two towers and that an auxiliary aircraft, having the necessary extra lifting power to more than balance the overload of the cruiser, is moored between the towers in a position over the cruiser and attached to the cruiser by two vertical lines with devices for measuring the tension therein, two similar lines also having tension-measuring devices are dropped from the cruiser to fixed points beneath. These lines are then pulled until all tower attachment lines are horizontal, after which ballast is shifted in both crafts, until the tension in the vertical lines is equal, or is in the predetermined ratio, showing that the center of buoyancy is over the center of gravity. Thereupon the aircraft may be launched in safety; and later on, when the cruiser has attained its flight speed, the tractor craft may be separated therefrom with the assurance that the vertical forces of weight and buoyancy are properly distributed for both ships.

In the practical application of the invention thus set forth, various devices may be employed in substitution for those which are herein shown as illustrating the principles involved; and variations may be made in many respects without departing from the scope of the invention. It is intended that the patent shall cover by suitable expression in the patent claims, whatever features of patentable novelty exist in the invention disclosed.

In the accompanying drawings;

Fig. 1 is a side elevation of an airship moored to a tower with a device for measuring the tension in a vertical line attached to the bow of the vessel;

Figs. 2, 3 and 4 show an elevation and sections, respectively on lines 3-3 and 4-4 thereof, of the tension-measuring device;

Fig. 5 is a side elevation, showing an airship moored between two towers with devices for measuring the unbalanced vertical forces at both ends of the vessel;

Fig. 6 shows a cruiser and a tractor aircraft attached to their moorings with devices for measuring tension in the suspended lines between the two and in the tie lines between the cruiser and fixed points beneath.

Fig. 7 gives a view of another form of this tension-measuring device.

In Fig. 1, the dotted lines show an airship 1' floating with horizontal keel and stern unrestrained, having its bow fastened by line 4' to the mooring tower 2. The winch 3 provides means for hauling in and paying out this line under control. It also handles another line 5' which leads vertically or approximately so, from a fixed point on the tower to the vessel's bow. In this latter line is a tension-measuring device 6. Previous to the launching of the airship on a flight, this

line 5 is pulled by the winch until line 4' becomes horizontal, the airship taking the position 1, where the full lines represent the same ship, and the indication of tension is noted. The stern is then tied to a fixed point beneath by line 23; and ballast or other weights are shifted on board the airship until the tension in line 5 is reduced to one-half of what it was previously, providing the center of buoyancy B is midway between stem and stern of the airship. In case the center of buoyancy is not so located, the weights are shifted until the tension is reduced in accordance with the proper predetermined ratio. Thus by the invention, it is possible to make sure that the center of buoyancy B is over the center of gravity G, previous to the launching of the craft, and accordingly that the airship when released from its moorings will rise with even keel and without having its vertical forces so distributed as to produce a rotating moment.

In case the airship is attached to its mooring tower by a rigid member, having for instance a ball and socket connection to the head of the tower, this invention provides for the measurement of the vertical force acting through such point of attachment whether acting in a downward or upward direction. Such measurement may be made by means of scales or other weight measuring machines well known in the art.

Figs. 2, 3 and 4 show details of a device for measuring or indicating tension of considerable magnitude, such as may exist in the vertical line 5 in connection with airships of large size. The tension scale is connected to the line by its ends 9, 10 and a group of stiff springs 12 are compressed as the tension in the line increases. As this occurs, the outer casing 7 and the inner casing 8 are drawn apart, revealing the lines marked on the inner casing. Count of the number of lines exposed indicates the amount of tension which is being transmitted through the scales. Fig. 7 shows the external view of another form of tension-measuring scales.

In Fig. 5 the airship is shown moored between two towers 2, 2' by lines 4, 4''. A line 5, 5'' at each end of the airship with tension-measuring devices 14 connected thereto, is used for pulling the airship down until its bow and stern are in a straight line between the points of tower attachment, after which ballast or weights are shifted on board until the tension in the lines 5, 5'' bears the predetermined relation one to the other, thereby indicating that the center of buoyancy of the craft is over its center of gravity. The stern is then tied to a fixed point by line 23; the tail tower 2' is moved away; and the connections to the airship are simultaneously released, thereby launching the craft on its flight.

In Fig. 6 is a cruiser airship of a type

which is the subject of a separate patent application, and an auxiliary aircraft or tractor, the use of which is also the subject of separate patent application, are shown 5 moored between two towers shown diagrammatically at 2 2'. Lines 18, having tension scales 14, attach the tractor to the cruiser; and lines 17, also equipped with tension scales 14, tie the cruiser to fixed points 10 beneath. Previous to launching, weights are shifted on both crafts until it is determined by means of the tension scales that the vertical forces acting on each vessel are properly distributed, not only to insure flotation 15 with even keel while connected together, but also to insure the same safe operating condition, when later on during flight they are separated.

The invention may be applied, in its 20 broader aspects, either by shifting ballast and cargo, to change the position of the center of gravity, or by shifting gas to change the center of buoyancy. Ballast and gas are shifted with aid of suitable ducts 25 and pumps on board. Under ordinary circumstances location of the center of buoyancy may be ascertainable by computation and observation more easily than the location of the center of gravity, because it results 30 from a few large gas spaces of easily ascertainable position and volume. But if the centre of gravity be known the apparatus of the invention can be used in connection with a shifting buoyancy on the 35 reversed application of the principles used in the foregoing example. When an airship having lighter-than-air gas is as a whole heavier than air, it may be desirable to resort to the corresponding use of the tension devices herein described by making connections 40 from ends of the ship to points above the airship, such as mooring towers and measuring or comparing the tension therein, and by computation ascertaining the vertical forces.

45 We claim as our invention:

1. The combination, with an airship floating in air, and having its center of gravity vertically under its center of buoyancy, of a vertical tie to the ground forward of said centres; a vertical tie to the ground aft of said centres; and indicating means whereby the tension in said ties is determined to be inversely proportional to the horizontal distances of the said ties from the vertical line 55 of said centres.

2. Launching equipment, including the combination, with an airship moored to a tower, of a tie extending to a distance from the tower and there holding one end of the ship; a vertical tie from said end of the ship to a fixed point below, whereby the said end is held so low that the stress in the first mentioned tie is free from vertical component; and means to indicate the tension in said 60 vertical tie.

3. In equipment for launching a moored airship, means to determine the vertical force exerted by the moored end of the ship; a vertical tie from the other end of the ship to a fixed point below it; and means to indicate the change in said vertical force resulting from change of relation between the center of buoyancy and the center of gravity of the ship. 70

4. The combination, with a moored airship having its axis in launching trim, of a forward vertical tie of the ship to the ground; an aft vertical tie of the ship to the ground; one of said ties being free from slack and also free from tension; and a tension indicating device in the other of said ties. 75

5. The combination, with a moored airship having its axis in launching trim, of means to detect presence of an upward force of the ship at its moored end; a vertical tie of the ship to the ground at its other end, free from slack and also free from tension; and means to indicate the increase of tension which results, in said tie, from alteration of the distribution of matter on board 80 the ship. 85

6. In equipment for launching an airship; two towers adapted to moor the head and tail of a ship floating in the air; a connection between the forward body of the airship and a fixed point at a lower elevation; a connection between the after body of the airship and a second fixed point at a lower elevation; means for exerting a pull in both of said connections; and means for indicating the change of tension in at least one of said connections consequent upon the alteration of distribution of matter on board 95 the ship. 100

7. In equipment for launching a cruising aircraft, heavier than the air displaced thereby, on its flight from a mooring, the combination of an auxiliary aircraft having a lifting power greater than that required for supporting itself in the air, means for attaching said auxiliary aircraft to said cruising aircraft, means for indicating the tension in said attachment means, means for attaching the cruiser aircraft to fixed points at a lower elevation, and means for indicating the tension in said latter attachment means. 110

8. The combination with a moored airship having its axis in launching trim, of a forward vertical tie of the ship to the ground; an aft vertical tie of the ship to the ground; and means for determining when said ties have their respective tensions inversely proportional to their respective distances from the center of buoyancy of the ship. 115

9. The combination with an airship of equipment for launching it from its mooring, comprising means for determining whether the center of buoyancy of said airship is in a position over the center of grav- 120 125 130

ity thereof, said means comprising two flexible connections from the airship, each to a fixed point at lower elevation, arranged to hold the airship in launching trim, and a 5 device for indicating the tension in one of said connections.

10. The combination with an airship of equipment for launching it from its mooring, comprising means for determining 10 whether the center of buoyancy of said airship is in a position over the center of gravity thereof, said means comprising two flexible connections from the airship to two fixed points at lower elevations arranged to 15 hold the airship in launching trim, and a device in each said connection for indicating the tension therein.

11. The combination with an aircraft of equipment for launching it from its mooring, comprising the combination of two ties 20 extending from the aircraft at points toward the respective ends thereof, two fixed places for attachment thereof at lower elevations, arranged to hold the aircraft in its 25 launching trim, and means for indicating the tension in at least one of said ties; the said ship, its mooring, and that one of its said two ties which is toward the mooring being arranged so that the mooring carries 30 the whole of the horizontal stress and the said tie associated therewith carries the whole of the vertical stress at the end of the ship which is moored.

12. In equipment for launching an airship from a position between two mooring towers when said airship is heavier than the air which it displaces, the combination of an auxiliary aircraft capable of exerting an upward pull on said airship, flexible connections 35 between this auxiliary aircraft and the airship, two flexible connections between the respective ends of said airship and two fixed points at lower elevations than said ends, and separate means for indicating the tension 40 in these two connections to the ends of the airship.

13. The combination with a mooring tower of apparatus for launching an airship which is lighter than the air displaced 50 thereby, comprising a flexible connection between the airship at a point toward its forward end and a fixed point at a lower elevation; a flexible connection between the airship at a point toward its rear end and a 55 second fixed point at a lower elevation; these two connections being arranged to hold the airship in launching trim; and separate means for indicating the tension in these two flexible connections thereby to detect the bringing of these tensions into predetermined relation to each other; whereby the airship, when released from these connections and from the mooring tower, may start its flight with its center of buoyancy 60 over its center of gravity.

14. Apparatus for launching from a position between two mooring towers an airship which is heavier than the air displaced thereby comprising flexible connections between the respective ends of the airship and fixed points at lower elevations than said ends, separate devices for indicating the tension in these two connections, and an auxiliary aircraft capable of exerting an upward pull on the airship, whereby the airship is lifted on its flight in a state of horizontal equilibrium. 70

15. In equipment for launching an aircraft, heavier than the air displaced thereby, on its flight from a mooring, the combination with said aircraft of an auxiliary airship having a lifting power greater than that required for supporting itself in the air; means for attaching said auxiliary airship to said aircraft and for detaching it 80 therefrom; means for indicating the tension in said attachment means; means for attaching said aircraft to fixed points at lower elevations; and means for indicating the tension in said latter attachment means; whereby it may be determined whether the vertical forces acting on said airship and said aircraft are properly distributed to insure safe launching of the aircraft. 85

16. In equipment for launching from a 95 mooring tower an airship which is heavier than the air displaced thereby, the combination of an auxiliary aircraft having a lifting power in excess of that required for its own support in the air, flexible connections between the auxiliary aircraft and the airship whereby the auxiliary aircraft may lift the airship in the launching thereof, and means for indicating the tension in said connections for determining whether the vertical forces acting on the airship are properly distributed to insure its safety during the launching operation. 100

17. The combination with an aircraft tethered to a mooring of means for eliminating from its tethering line all stresses having vertical components, including means for attaching said aircraft in its launching trim to fixed points at lower elevations and for detaching it therefrom, and means for indicating the stress in said attachment means, whereby it may be determined whether the vertical forces acting on said aircraft are properly distributed to insure the safe launching thereof. 110

18. In equipment for launching an airship when floating in the air and moored by guy lines, the combination with the airship and its guy lines, of means separating the horizontal mooring stresses from the vertical mooring stresses and means applicable to the vertical stresses whereby it may be determined whether the center of buoyancy of the airship is over its center of gravity. 125

19. Apparatus for putting an airship into 130

trim for flight from a mooring, comprising the combination with the head end mooring tie for the ship of a vertical tie for the ship near the end thereof where the mooring tie is attached, and a vertical tie for the ship near the other end of the ship; the said vertical ties having each such length that the mooring tie runs horizontally when they are taut; and the said vertical ties each containing a tension indicating means within

its line, whereby in ascertaining the balance of the ship substantially all net lifting effects of wind forces on the ship and all vertical components of the stress in the mooring tie are eliminated. ¹⁵
